UNITED STATES PATENT OFFICE.

OLE M. MATHISEN, OF LA CROSSE, WISCONSIN, ASSIGNOR, BY MESNE ASSIGNMENTS, OF ONE-HALF TO WHEELING CAN COMPANY, OF WHEELING, WEST VIRGINIA, A CORPORATION OF WEST VIRGINIA; OTTO M. SCHLABACH, OF LA CROSSE, WISCONSIN, ADMINISTRATOR OF SAID MATHISEN, DECEASED.

MEANS FOR ATTACHING HANDLES TO CONTAINERS.

1,142,112.

Specification of Letters Patent. Patented June 8, 1915.

Application filed October 28, 1910. Serial No. 589,559.

To all whom it may concern:

Be it known that I, OLE M. MATHISEN, a citizen of the United States, residing at La Crosse, in the county of La Crosse and State 5 of Wisconsin, have invented certain new and useful Improvements in Means for Attaching Handles to Containers, of which the following is a specification.

This invention relates to handle-attaching 10 means of the character disclosed in the patent to Morse, No. 830,095, issued Sept. 4, 1906.

The object of this invention is to provide an improved handle-attaching means which 15 will securely hold the handle-engaging clip against rotation with reference to the container wall, which forms a fluid-tight joint with the wall, and which holds the handle and its clip closely alongside the container.

20 In the accompanying drawings, Figure 1 is a side elevation of a can provided with a handle-attaching means embodying the features of my invention. Fig. 2 is a fragmentary side elevation of the container, 25 showing the attaching means in side elevation. Fig. 3 is a vertical central section through the attaching means and a portion of the container, taken in the plane of line 3 3, Fig. 2. Fig. 4 is a sectional view of 30 the parts separated. Fig. 5 is a section on line 5 5 of Fig. 2. Fig. 6 is a sectional view of a modification. Figs. 7 and 8 are dia- 35 grammatic views of the two forms, showing the positions the parts assume when clenched together.

Referring to the drawings, A represents 40 a container provided with handles B of any suitable form. As herein shown, the handles are in the form of a closed loop, and com- 45 prise portions B' adapted to be gripped in the hand, and bars B² at the opposite side of the loop adapted to be engaged by the attaching means.

The attaching means comprises a clip 1 45 consisting of a piece of sheet metal bent double, in the present instance, to provide a loop 2 adapted to encircle the bar B² of the handle. The end portions 3 and 4 of the said piece of sheet metal have openings 50 5 and 6 formed therethrough. In forming the opening 5 suitable tools may be used to provide a flange surrounding the edge of the opening, said flange extending through

the opening 6, as shown most clearly in Fig. 4. The wall of the container A has an 55 opening A' formed therein adapted to receive the flange 7 upon the clip 1 when the parts are assembled, and said wall has an inwardly extending flange A² surrounding the opening A' and adapted to telescope 60 with the flange 7.

Suitable means is provided for holding the flange 7 in the opening A' in the wall A, and for closing the openings in said wall and in the clip 1 to prevent the escape of 65 material therethrough. This means in the present instance comprises a securing member 8 formed in two sections, the cup section 9 having an outstanding annular flange 10 at its edge, which flange is engaged by 70 an overlying annular flange 11 at the edge of the disk section 12 of said securing member. The parts of the member 8 are thus held securely together.

In securing the clip 1 to the side of a container, the flange 7 on said clip is inserted through the opening A' in the container, as hereinbefore described, and the securing member 8 is inserted in the openings 5 and 6 in the clip 1 from the inner side of the 80 container. When the parts are thus brought together, the flange 7 on the clip and the flange A² on the container wall lie within the flange 11 at the edge of the section 12 of the securing member 8. 85

When the parts are in the position just described, the flanges 7, A² and 11 and the edge of the cap 6 are clamped or compressed together as shown in Figs. 3 and 7 by any suitable means not shown. In thus 90 compressing said parts, the edges of the flanges 7 and A² are spread outwardly to interlock with the inturned flange 11 upon the cap, and the parts are thus rigidly secured together. The cup section 9 assists 95 in holding the flange 7 in place.

In the modified form illustrated in Figs. 6 and 8, a flange 13 is formed on the member 4 of the clip 1, said flange surrounding the opening 6 and telescoping with the 100 flange 7. When this form of clip is used, the flange A² upon the container wall is omitted. It will be understood that a suitable securing member such as 8 will be used to lock the clip to the container wall in the manner 105 hereinbefore described.

In order to hold the upper portion of the clip and the handle B closely alongside the container, I provide one or more stiffening ribs 14 on the clip, said ribs acting as braces 5 to prevent the clip from bending outwardly away from the can. These ribs 14 are formed in the present instance by providing straightened portions of the sheet metal at the point where the loop 2 merges into the 10 end member 3 of the clip, as clearly shown in Fig. 5.

It will be seen that the handle-engaging clip is securely clamped to prevent rotation thereof, and lies closely alongside the can. 15 When the parts of the attaching means are clenched together an absolutely fluid-tight joint is formed.

While I have hereinbefore described my invention in considerable detail, I recognize 20 the fact that the form and proportion of certain of the parts may be changed without departing from the spirit and scope of the invention. I therefore do not wish to be limited to the exact details herein shown 25 and described.

I claim as my invention:

The combination of a container having an opening in one wall, a handle-engaging member lying along the outer face of said

wall and having a similar sized opening 30 therein registering with the opening in said wall, said handle-engaging member having a laterally extending annular flange integral therewith at the edge of the opening therein, said flange fitting in and extending 35 through the opening in the container wall, and a securing member positioned at the inner side of the container wall and arranged to close the opening therein, said securing member comprising a cup-shaped element 40 projecting outwardly through said opening and fitting within said flange to assist in holding the latter in place, and a disk element closing the cup and having an annular integral flange running about its periphery 45 and engaging the cup element to secure said elements together, the last mentioned flange surrounding the inner edge of the flange on the handle-engaging member, the parts being 50 compressed to rigidly interlock them together.

In testimony whereof I affix my signature in presence of two witnesses.

OLE M. MATHISEN.
